UNITED STATES PATENT OFFICE.

CHARLES H. MANN, OF HADDONFIELD, NEW JERSEY.

SAFETY-ENVELOP.

SPECIFICATION forming part of Letters Patent No. 698,300, dated April 22, 1902.

Application filed October 23, 1901. Serial No. 79,701. (No model.)

To all whom it may concern:

Be it known that I, CHARLES H. MANN, a citizen of the United States, residing at Haddonfield, in the county of Camden and State of New Jersey, have invented new and useful Improvements in Safety-Envelops, of which the following is a specification.

My invention relates to safety-envelops, and more particularly to those adapted to be closed through the medium of a seal of wax or like material—such, for instance, as is disclosed in Letters Patent of the United States No. 674,785, granted May 21, 1901, to myself and Clinton A. Higbee, and is designed to combine with the novel sealing feature set forth in said Letters Patent an improved construction of envelop that will be when sealed incapable of being tampered with to abstract the contents without breaking the seal and also tearing the envelop.

The invention also embodies certain other novel features, as will be hereinafter more definitely pointed out, reference being had to the accompanying drawings, in which—

25 Figure 1 is a plan view of an envelop-blank embodying the preferred form of construction. Fig. 2 is a similar view of said blank formed into the envelop, the sealing-flaps being left open for the reception of the contents. Fig. 30 3 is a longitudinal sectional view of the same, taken on the line 3 3, Fig. 2. Fig. 4 is a transverse sectional view taken on the line 4 4, Fig. 2. Fig. 5 is a view similar to Fig. 4, the inner sealing-flap being shown closed. Fig. 35 6 is also a view similar to Fig. 4, the envelop being shown closed and sealed. Fig. 7 is a plan view of a blank, illustrating a slightly-modified construction. Fig. 8 is a view of the envelop formed from the blank shown in Fig. 40 7, the same being shown partly folded. Fig. 9 is a longitudinal sectional view of said envelop. Fig. 10 is a similar view taken through the seal, showing the envelop closed and sealed and illustrating a slightly-modified construction of the seal.

45 Similar numerals of reference indicate corresponding parts in the several views.

Referring more particularly to Figs. 1 to 6, the reference-numeral 1 denotes the front side of the envelop, the same being extended at its upper edge into the usual closing-flap 2, and 3 the back side, extended at its lower

edge into a supplemental closing-flap 4, somewhat narrower than the flap 2, for a purpose hereinafter to be described. The back piece 55 3 is provided on each side with a narrow flap 5, while the front piece has attached thereto the usual side flaps 6.

To form the envelop ready for the reception of articles to be transported, the flaps 5 are 60 first folded along the lines 7, and, together with the back piece 3, are then folded upon the front piece 1 along the line 8, the sides of said flaps 5 then contacting with the front piece 1, being united thereto by gum in the 65 usual manner. The flaps 6 are then folded over onto the back piece 3 along the lines 9 and gummed thereto, and the envelop is ready for the reception of articles, as shown in Figs. 2 and 3.

70 By reason of the fact that the supplemental flap 4 is somewhat narrower than the flap 2 the former will not cover the upper edge of the latter when in the position shown in Fig. 2, and the two flaps when in such position 75 may not only be gummed at one operation, but may also be moistened at one operation when it is desired to seal the envelop.

In using the envelop the contents are inserted thereinto between the flaps 2 and 4, 80 the flap 4, after having its gummed edge moistened, is folded down against the inner side of the front piece 1 and sealed thereto, as shown in Fig. 5, and then the main flap 2 is folded over onto the side flaps 6 and sealed 85 thereto.

In connection with this envelop I have illustrated the novel seal disclosed in the Letters Patent hereinbefore referred to, the same consisting of an apertured disk 10, attached 90 to the under side of back piece 3 and registering with an aperture 11 therein, the back of said disk being closed in any suitable manner, as by a piece of material 12, attached thereto. The central end of flap 2 when 95 folded will overlie said aperture 11, and by applying thereto sealing-wax or other suitable sealing medium a design sealing-stamp may impress therein a seal below the surface of the back piece 3 and at the same time confine 100 the end of flap 2 thereunder.

By referring to Fig. 2 it will be observed that when the side flaps 6 are folded they carry with them at their upper edge small

triangular-shaped pieces 13, that are to be gummed when the flaps 2 and 4 are gummed and which fold down with flap 2 and unite with side flaps 6. It will thus be seen that the 5 flaps 2 and 4 afford a double thickness for the upper edge of the envelop. The flaps 5 and 6 afford a similar double thickness for the side edges thereof, and the triangular pieces 13 effectually close the upper corners thereof 10 and prevent any possible abstraction of the contents at these points.

In Figs. 7, 8, and 9 I have illustrated a slightly-modified construction, the flaps 5 being folded up with back piece 3 and then 15 folded inward with side flaps 6 against the outer side of back piece 3.

In Fig. 10 is illustrated a modified construction of the seal, the piece 12 on the back of disk 10 being omitted, so that the sealing- 20 wax or other sealing material will come in contact with the contents of the package, and thus seal the contents to the envelop. This construction is intended for use particularly 25 when paper money is being transported, the package of money being first surrounded by the usual paper or linen bank-note strap 14, which underlies the aperture in the disk 10 and receives the sealing-wax thereon, thus firmly uniting the money-package to the envelop. 30

Having thus described my invention, what I claim as new, and desire to secure by Letters Patent, is—

1. In a safety-envelop, a front piece and a 35 back piece, the two when the envelop is formed lying in contact and constituting the closure, side flaps for retaining said front and back pieces in position, and a closing-flap upon each of said front and back pieces, said flaps

when the envelop is formed lying one against the other and having adhesive material on like faces thereof, the outer flap having its sealing-surface projecting beyond the edge of the inner flap, whereby the two gummed flaps are adapted to be moistened together. 40 45

2. In a safety-envelop, a front piece and a back piece, the two when the envelop is formed lying in contact and constituting the closure, inner side flaps attached to one piece and adapted to be sealed against the inner 50 side of the other piece, outer side flaps attached to the other piece and adapted to be sealed against the outer side of the first piece, and a closing-flap upon each of said front and back pieces, said flaps when the envelop is 55 formed lying one against the other and having adhesive material on like faces thereof, the outer flap having its sealing-surface projecting beyond the edge of the inner flap, whereby the two gummed flaps are adapted 60 to be moistened together.

3. In a safety-envelop, the body portion having an aperture therein for the reception of a sealing medium, an apertured disk underlying and surrounding said aperture, a 65 closing-flap adapted, when closed, to partially overlie said apertures, in combination with a confining-strap for the contents adapted to underlie said apertures and form the base for the reception of the sealing medium. 70

In testimony whereof I have hereunto set my hand in the presence of two subscribing witnesses.

CHARLES H. MANN.
